[57] CLAIM

The ornamental design for a bobeche for a lighting fixture of
FIG. 1, as shown and described.

DESCRIPTION

FIG. 1 is a side elevational view of a bobeche for a lighting
fixture according to this invention. The view of the side
opposite is the same;

FIG. 2 is a cross sectional view taken along the lines 2—2
of FIG. 1;

FIG. 3 is a bottom plan view of the bobeche for a lighting
fixture of FIG. 1; and,

FIG. 4 is a top plan view of the bobeche for the lighting
fixture of FIG. 1 on an enlarged scale.
